UNITED STATES PATENT OFFICE.

WILLIAM P. PARSONS, OF CORNING, NEW YORK, ASSIGNOR TO CORNING GLASS WORKS,
OF CORNING, NEW YORK, A CORPORATION OF NEW YORK.

DESIGN FOR A BOTTLE.

Application filed September 17, 1921. Serial No. 501,465. Term of patent 14 years.

To all whom it may concern:

Be it known that I, WILLIAM P. PARSONS, a citizen of the United States, residing at Corning, in the county of Steuben and State of New York, have invented a new, original, and ornamental Design for a Bottle, of which the following is a specification, reference being made to the accompanying drawings, forming part thereof.

Figure 1 is a side elevation of a bottle, showing my new design.

Figure 2 is an end elevation of the bottle, shown in Figure 1.

I claim—

The ornamental design for a bottle, as shown.

WILLIAM P. PARSONS.
